UNITED STATES PATENT OFFICE

2,140,135

NOISE REDUCING DEVICE FOR ADDING MACHINES AND THE LIKE

Walter W. Landsiedel, Norwood, Ohio, assignor to Remington Rand Inc., Buffalo, N. Y., a corporation of Delaware

Application May 20, 1936, Serial No. 80,701

1 Claim. (Cl. 235—1)

My invention relates generally to adding and like machines and more specifically to means for reducing operating noises in these machines which noises may be due to the various actions of parts therein, since most of said parts are made of metal, and also to the vibrating of cover against base, etc.

The main object of my invention is, therefore, to generally reduce noises incident to the operation of adding machines and the like, by absorbing and insulating the internal vibrations and shock imparted to the bases and covers of said machines.

A further and more specific object of this invention lies in a special base plate construction which permits an unusual absorption of both vibration and shock.

Another object is to produce a sound-reducing casing for adding and similar machines which shall be simple of construction and easy of assembly.

In the accompanying drawings and description, I shall illustrate my invention as constructed specifically for use on machines of the type shown in United States patent to Mehan 1,899,444, although it is quite evident that the invention herein set forth may be as well applied to any other machine.

One form of the invention is illustrated in the accompanying drawings in which:

Fig. 1 is an elevation of the right hand side of a machine casing embodying my invention.

Fig. 2 is a fragmentary front elevation of the same partly in section.

Fig. 3 is an exploded isometric view of the base plate inverted, showing the special construction thereof and also showing the insulating and damping materials used therein.

Fig. 4 is a bottom plan view of all the base pads placed in the position they assume in the machine base.

Like characters of reference refer to like parts in all views.

Referring to the drawings in detail, I represents the base plate (Fig. 3), which was made solid except for the motor ventilating hole 2, previous to my present invention. The under side of base 1 is constructed with strengthening ribs indicated at 3, 4, 5, 6, and 7, respectively, as shown in the drawings. This construction forms pockets 8, 9, 10, 11, and 12, which heretofore had solid tops integral with and as part of base 1.

An important part of my invention lies in cutting openings 13, 14, 15, 16, and 17, respectively, in the tops of these pockets, each similar in

shape to its respective pocket but smaller than the tops of these pockets, so that damping strips 13a, 14a, 15a, 16a, and 17a, which may be made of felt or any other suitable material, may fit snugly into their respective pockets and receive and absorb or damp much of the noise usually forthcoming at these points. It will be noted that the openings 13, 14, 15, 16, and 17, permit a large quantity of the vibrations to pass directly to the damping strips without impinging upon the base. Strips 13a, etc. are backed with pieces 18 of any suitable fibrous insulating material which greatly absorb the shock and vibrations caused by the operating mechanism in action.

A retaining plate 19, made to conform to the external contours of base plate 1, maintains the above mentioned felts and fiber pieces in constant and intimate contact with each other and with their respective pockets and at the same time allows the machine to be lifted in the regular manner by means of formed portions 21 and 22 having similar shapes to hand-pole openings 23 and 24.

Considering now the machine cover, designated herein as 26 (Fig. 3), this cover previously caused a large proportion of noise in the machine because of vibrations transmitted directly to it from the edges of the base plate 1, and also by sound waves, set up by the moving machine parts, striking it at various points. These vibrations of the cover 26 were further amplified upon consecutive repeat operations of any parts.

Machine cover noises and vibrations are almost entirely eliminated in my invention by use of an insulating strip 25 which very effectively absorbs them. The insulating strip 25 is adhesively secured to cover 26 on the inside and extends beneath the bottom edge thereof, thus forming a cushioning and damping element between cover and base.

Screws 20 fasten the retaining plate 19 and base plate 1 together and screws 28 fasten base plate 1 and machine cover 26 together, these parts being insulated each from the other by the insulating pieces and strips mentioned above, thus giving a solid construction and at the same time reducing noise throughout the machine to a minimum.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention.

as hereinbefore set forth, and as hereinafter claimed.

What I claim as new, and desire to secure by Letters Patent, is:

- 5 A casing for adding and like machines including a cover member, a base member formed with

ribs and openings adjacent to said ribs, vibration insulating and absorbing elements in said base member and covering said openings, and a securing member for holding said elements in place.

WALTER W. LANDSIEDEL.
